UNITED STATES PATENT OFFICE

2,422,705

DISPENSING PACKAGE FOR COMMODITY STICKS.

Gordon Saint Clair, Chicago, Ill.

Application March 28, 1942; Serial No. 436,571

3 Claims. (Cl. 206—56)

1

My present invention relates in general to the art of packaging and has more particular reference to the packaging of material in sticks or bars adapted to be consumed progressively from one end of the stick toward the other, the present invention pertaining specifically to an improved method and means for packing a commodity, such as lip rouge, shaving soap, deodorant sticks, styptic pencils, cream sticks, and other commodities of like character put up for use in sticks or bars, the package of my present invention allowing for the progressive consumption of the packaged commodity from one end of the stick or bar toward the other.

An important object of my present invention is to provide a shortenable container for a commodity in stick form so that the package may be progressively shortened as the commodity stick is consumed from one end thereof; a further object being to employ interfitting sections of identical form to provide a commodity stick package progressively shortenable from one end thereof by the successive removal of the sections thereof.

Another important object of the invention is to provide a commodity stick package comprising interfitting bands, each having a stick embracing neck portion and a skirt portion of enlarged size adapted to snugly and frictionally receive the neck portion of an adjacent interfitting band, whereby several interfitting bands may form a shortenable sheath about the commodity stick; a further object being to provide a base having a neck portion to grippingly receive an end of the commodity stick and to frictionally interfit within the skirt portion of the band at one end of the sectional sheath to support the same in position embracing the commodity stick; a still further object being to provide an outer cover, closed at one end and open at the other, for removably engaging said base in position enclosing said sectional sheath; a further object being to form the casing with an internal shoulder in position to engage the band at the end of the sectional sheath remote from the base to aid in retaining the sheath and the commodity stick in place on the base.

Another important object is to form the cover of transparent material whereby to reveal the commodity stick and sectional sheath through the cover; a further object being to form the bands comprising the sectional sheath of transparent material.

Another important object is to make the bands of colored material, thus affording an opportunity

2

to employ bands of unlike color in a sheath for artistic purposes.

Another important object is to notch, perforate, or otherwise cut away portions of the bands in order to create decorative effects; a further object being to cut away the skirt portions of a band of one color in order to reveal therethrough the neck portion of an interfitting band of another color.

10 Another important object is to provide a commodity stick container that may be made to any desired sectional shape, the package of my present invention being in nowise limited to commodity sticks of circular sectional shape.

15 Another important object is to provide a package of the character mentioned, all of the parts of which may be fabricated as plastic moldings, although, of course, the parts may be made of metal, paper, or other material, if desired.

20 Another important object is to provide a package of the character mentioned, including an open-ended cover having an internal shoulder facing the open end and adapted to receive and support the bands forming the sectional sheath

25 assembled therein as a preliminary assembly operation, so that by attaching one end of the commodity stick in the base, as another assembly operation, the commodity stick may be finally packaged merely by pressing it, with base attached at one end, endwise into the cover supported sectional sheath.

30 Among the other numerous important objects and advantages of the present invention is the provision of a low cost, convenient commodity 35 stick package, including the structure of the package which aids in assembling the commodities therein; the provision of a package made of inexpensive parts requiring a minimum number of fabricating dies; the provision of a package

40 allowing novel eye arresting decorative features to be incorporated therein at minimum expense; the provision of a package that can be applied to commodity sticks of any size and sectional shape; and, in general, the provision of a package 45 of the character mentioned which presents an end of the commodity stick at all times in position to be consumed, without resort to stick protecting mechanism.

50 These and numerous other important objects, advantages, and inherent functions of the invention will be fully understood from the following description, which, taken in connection with the accompanying drawings, discloses a preferred 55 embodiment of the invention.

Referring to the drawings:

Figure 1 is a perspective view of a commodity stick package embodying my present invention;

Figure 2 is an enlarged sectional view taken substantially along the line 2-2 in Figure 1;

Figure 3 is an enlarged perspective view, partially in section, of an element of the package;

Figure 4 is a sectional view, drawn to reduced scale, and taken substantially along the line 4-4 in Figure 2;

Figure 5 is a perspective view, partially in section, showing the commodity stick supporting base element of the package;

Figure 6 is a perspective view, partially in section, showing a modified form of stick supporting base;

Figures 7, 8 and 9 are sectional views showing sectional shapes to which the container may be made;

Figure 10 is a sectional view through a package embodying the invention;

Figure 11 is a perspective view showing an element of the package shown in Figure 10;

Figure 12 is a perspective view of a package element showing how it may be formed with cut out portions for decorative purposes; and

Figures 13, 14 and 15 are sectional views illustrating various artistic effects that may be accomplished in packages made in accordance with the teachings of the present invention.

To illustrate the invention, I have shown on the drawings a commodity stick package 11 comprising a base 13 adapted to receive and support one end of a commodity stick 15 which may comprise a stick of lip rouge, shaving soap, deodorant or styptic material, or other commodity in bar or stick-like form and adapted for consumption from the base remote toward the base mounted end thereof.

The package may include a removable cover 17 having a closed end and an open mouth adapted to fit upon a shoulder 19 formed on the base. The open end of the cover may thus frictionally grip the shoulder 19 in order to retain the cover on the base, or interfitting latch means may be provided, as by forming a small button or projection on the shoulder 19 and a cavity on the inner wall of the cover at its open end in position to latchingly receive the button or projection on the base. The base 13 is formed with a cavity 21 for the snug reception of the end of the commodity stick, and this cavity may be formed with suitable means for retaining the stick in the base.

The package shown in Figures 1 to 5 is of rectangular sectional shape and is especially suited for use as a container for lipstick, since the rectangular shape allows the usable end of the stick to be presented as a chisel edge for convenient application.

The package, as shown in Figures 6 and 10, has circular sectional shape and is well adapted for use as a container for shaving soap sticks and other commodities in sticks having cylindrical surfaces. As shown in Figures 6 and 10, the base 13 may be formed with screw threads 23 on the inner surfaces of the cavity 21 to threadingly receive the end of the stick, or, as shown in Figures 2 and 5, holding lugs 25 may be formed on the inner wall of the cavity in position to project into the material of the commodity stick in order to hold it in place. The threaded arrangement shown in Figures 6 and 10 is particularly well adapted for the retention of shaving soap sticks, while the lugs 25 are well adapted for the reten-

tion of sticks comprising relatively soft material such as lip rouge. In order to aid in assembling the commodity stick in the base, the latter may be formed with vent openings 27 which, as shown in Figures 6 and 10, may extend through the bottom of the base, but the vent openings may, as shown in Figures 2 and 5, be arranged in the cavity-forming side walls of the base.

The base 13 supports a sectional sheath 29 comprising a plurality of interfitting bands 31. These bands preferably each comprise a neck portion 33, adapted to snugly embrace the lateral surfaces of the commodity stick, and a skirt portion 35 having an inner diameter sized to snugly and frictionally receive and embrace the outer surfaces of the neck portion 33 of an adjacent band so that a series of bands may be assembled in interfitting end-to-end relationship to provide the sectional sheath 29. Each band is preferably formed at the junction of its neck and skirt portion to provide an outer shoulder 37 facing the neck end of the band in position to engage the edge of the skirt portion of an adjacent band embracing said neck portion, and an inner shoulder 39 facing the skirt end of the band to engage the end of the neck of the adjacent band fitted therein. The edge of the band defining the neck portion 33 is rounded, as shown at 41, and the shoulder or seat 39 is preferably similarly rounded.

The upper portions of the walls defining the cavity 21 in the base are preferably formed to provide a groove 43 similar to the band groove or shoulder 37, the groove 43 extending inwardly of the shoulder 19 to receive the skirt portion of the band at one end of the sectional sheath 29; and the walls of the base are also preferably formed to provide a neck portion 45 inwardly of the groove 43 and having outer surfaces shaped in conformity with the band neck portion 33 so that said neck portion 45 may snugly and frictionally fit within the skirt portion of the band at one end of the sectional sheath. To this end, the outer surfaces of the neck portion 45 are rounded to fit the seat 39 of said end band of the sheath.

The cover 17 also, as shown in Figure 10, may be formed with an internal shoulder 47 spaced from the closed end of the cover, said shoulder facing the open end of the cover and being positioned, when the cover is mounted on the base, to engage the shoulder 37 of the band which forms the base remote end of the sectional sheath. The cover, when mounted on the base, thus serves to aid in retaining the bands of the sectional sheath pressed down the one upon the other and upon the base.

The commodity may conveniently be assembled in the package by first assembling a sufficient number of bands in interfitting relationship to form a sheath of appropriate length. The so assembled bands may then be dropped into the cover through the open end thereof, the shoulder 47 serving to support the sectional sheath in position in the cover. The commodity stick may be assembled in the base, whereupon the base may be used as a holder for pressing the stick endwise through the sectional sheath until the base enters the open end of the cover 17 and the groove 43 engages the skirt of the end band of the sheath.

The base may be provided with an outstanding flange 49 in position to engage the open end of the cover, said flange 49 being preferably knurled, as at 51, to facilitate the grasping of the base in removing the cover therefrom in order to un-

cover the base remote end of the commodity stick for use, the same being accomplished merely by holding the knurled edge of the base and pulling the cover therefrom, sufficient clearance being afforded between the inner surfaces of the cover and the outer surfaces of the skirt portions of the sheath so that the cover will slide freely upon the sheath, leaving the sectional bands firmly in place. In order to make sure that the bands remain in interfitted position, the inner surface of the skirts 35 and the outer surfaces of the necks 33 may be provided with co-operating latching means for securing the parts together, although the provision of such latching means ordinarily is unnecessary, since the parts may be formed for snug frictional interfitting engagement sufficient to maintain the sheath in place.

The shoulder 47 may be formed as an inwardly extending lug or flange, or as a plurality of fingers. The outer surfaces of the cover preferably have uniform sectional dimensions from the closed end thereof to the open end. If desired, I may knurl or otherwise roughen portions of the surface of the cover, thus improving the appearance of the package and affording a convenient non-slipping hand hold that may be used in removing the cover from the base to uncover the commodity stick for use. To reduce weight, the bottom of the base 13 may be made hollow, as shown in Figures 2 and 5, or the base may be made solid, if weight be unimportant.

After the cover has been removed, the commodity may be used by employing the sectional sheath 29 as a hand hold for manipulating the commodity stick. To this end, the outer surfaces of the skirt portions of the bands forming the sectional sheath may be knurled or otherwise roughened to provide a non-slipping hand hold. The commodity stick, as packaged, has an end projecting outwardly of the base remote end of the sectional sheath. As the commodity is consumed at said exposed end and is thus worn down toward the said base remote end of the sheath, the sections or bands 31 may be progressively removed by detaching them from the sheath and sliding them off of the worn end of the commodity stick to thereby uncover an additional portion of the stick. The sectional sheath may thus be removed until the commodity stick is worn down to the base. The removable cover 17, however, may continue in use as such throughout the consumption of the commodity stick.

It will be obvious that the package of my present invention can be made of any suitable preferred or convenient material. For example, the bands 31 may be built up of paper or cardboard or may be made of metal. The cover and base also may be made of paper or cardboard suitably formed by pressing or other forming or molding process. I prefer, however, to form all of the elements of the package of moldable plastic material, and in this connection, it will be seen that all of the parts of the package may be made from three molding forms or dies, the bands of the sectional sheath being identical parts.

It will be noted also that the package may be made as indicated in Figures 4, 7, 8 and 9 to accommodate commodity sticks of any desired sectional shape, including oval as well as circular shapes, and also square, rectangular, triangular, polylateral, fluted and prismatic shapes, the ability to accommodate sticks of any desired sectional configuration being one of the valuable aspects of my present invention.

As shown in Figures 11 and 12, the skirt por-

tions 35 of the bands may be notched or cut away or perforated in accordance with any desired design. Figure 11, in dotted lines, shows the possibility of forming semicircular notches 59 in the skirt portion 35, and square, triangular, or other preferred shapes may be formed in the edge of the skirt, if desired. Figure 12 shows the possibility of decorating the skirt portion 35 by forming openings of various shape therein, the skirt 10 being shown formed with circular perforations 61, a star opening 65, slits 67, and square openings 69. In Figure 14, adjacent bands are shown formed with square notches 57, semicircular notches 59, circular perforations 61, triangular notches 63, quadrilateral perforations 67, star shaped openings 65 and combination slit 67, and circular perforations 61 in the skirt portions of the bands.

I may provide an almost unlimited number 20 of extremely novel effects in packages embodying my present invention by forming adjacent bands of differently colored material in the sectional sheath. As shown in Figure 13, bands 73 of white material are used in combination with bands 75 of blue material and bands 77 of red material which, when used with a commodity stick comprising red lip rouge, provides a package having an attractive red, white and blue banded appearance.

I may also employ bands of various colors to 30 create interesting and eye arresting effects by suitably perforating or notching the skirts 35 of the bands to reveal through the openings, in a skirt of one color, the neck of an adjacent band 35 of a different color, an example of such construction being illustrated in Figure 15, wherein white bands 73 having square cut-outs 51 are used alternately with bands 77 of red material formed with square cut-outs 51, the notches in the white bands 73 revealing portions of the necks of the red bands 77 therethrough, and vice versa, in order to produce a red and white striped effect in the package. In the arrangement shown in Figure 15 also, a white band 73 formed with star-shaped 40 openings 65 is shown used with a blue base 75, in order to provide blue stars on a white background. It will be noted that the effect embodied in the device shown in Figure 15 is accomplished by assembling the adjacent bands in the proper 45 relative angular relationship, and in order to maintain the bands in such relationship, in a package of circular section, it may be desirable to form the interfitting skirts and necks with interfitting projections and grooves to prevent relative turning of the bands while permitting the bands to be successively removed. In packages of non-circular sectional shape, each band is 50 splined with the adjacent bands, whereby relative turning of the bands with respect to each other and the base is prevented.

It is within the contemplation of my present invention to make the cover 17 of transparent material so as to reveal the bands 31 and the commodity stick therethrough. It is also within 65 the contemplation of the invention to make the bands 31 themselves of transparent material so that the color, texture and quality of the packaged commodity may be revealed without opening the package; and, of course, the employment of a transparent cover 17 is especially effective where decorative effects are embodied in the package through the use of varicolored bands, or where the bands have been perforated or notched as described.

It is thought that the invention and its nu-

merous attendant advantages will be fully understood from the foregoing description, and it is obvious that numerous changes may be made in the form, construction and arrangement of the several parts without departing from the spirit or scope of the invention, or sacrificing any of its attendant advantages, the form herein disclosed being a preferred embodiment for the purpose of illustrating the invention.

The invention is hereby claimed as follows:

1. A package for a commodity stick comprising a base forming a mounting for one end of the stick and a tubular sectional sheath on said base and enclosing the lateral surfaces of the stick, said sheath comprising interfitting collar elements, each having a neck portion for snugly embracing the stick and a larger skirt portion for snugly embracing the neck portion of an adjacent collar element, in frictional engagement therewith, the base having a neck portion of shape duplicating that of the neck portions of said collar elements and the skirt portion of the collar element adjacent said base snugly embracing and frictionally engaging the neck portion of said base, the collar elements being arranged and conformed so that the same may be demounted, successively, from the base remote end of the stick, as the same is consumed, by sliding the endmost collar element, axially, from mounted position at the base remote end of the stick, to thereby uncover a portion of the stick for consumption, the interfitting portions forming means frictionally securing adjacent collar elements together in axial alignment to form the sheath.

2. A package for a commodity stick of non-circular sectional configuration comprising a base forming a mounting for one end of the stick and a tubular sectional sheath of non-circular sectional configuration on said base and enclosing the lateral surfaces of the stick, said sheath comprising interfitting collar elements of non-circular sectional configuration, each having a neck portion for snugly embracing the stick and a larger skirt portion for snugly embracing the neck portion of an adjacent collar element, in frictional engagement therewith, the base having a neck portion of shape duplicating that of the neck portions of said collar elements and the skirt portion of the collar element adjacent said base snugly embracing and frictionally engaging the neck portion of said base, the collar elements being arranged and conformed so that the same

may be demounted, successively, from the base remote end of the stick, as the same is consumed, by sliding the endmost collar element, axially, from mounted position at the base remote end of the stick, to thereby uncover a portion of the stick for consumption, the interfitting portions forming means frictionally securing adjacent collar elements together in axial alignment to form the sheath.

3. A package for a commodity stick comprising a base forming a mounting for one end of the stick and a tubular sectional sheath on said base and enclosing the lateral surfaces of the stick, said sheath comprising interfitting collar elements, each having a neck portion for snugly embracing the stick and a larger skirt portion for snugly embracing the neck portion of an adjacent collar element, in frictional engagement therewith, the base having a neck portion of shape duplicating that of the neck portions of said collar elements and the skirt portion of the collar element adjacent said base snugly embracing and frictionally engaging the neck portion of said base, the collar elements being arranged and conformed so that the same may be demounted, successively, from the base remote end of the stick, as the same is consumed, by sliding the endmost collar element, axially, from mounted position at the base remote end of the stick, to thereby uncover a portion of the stick for consumption, the interfitting portions forming means frictionally securing adjacent collar elements together in axial alignment to form the sheath, the skirt portion of at least one of said collar elements being cut away to form openings revealing, through said openings, the neck portion of an adjacent element enclosed within the skirt portion having said openings.
